UNITED STATES PATENT OFFICE

GIUSEPPE COSENTINO, OF CLEVELAND, OHIO

CLOCK

Application filed November 8, 1928. Serial No. 317,950.

This invention relates to clockwork and has special reference to a clock mechanism requiring winding but once in a long period of time such as once in four hundred days, the device being preferably termed a four hundred day clock.

One important object of the invention is to improve the general construction of clocks of this description.

A second important object of the invention is to provide improved means for driving the main arbor of such a clock.

A third important object of the invention is to provide novel means whereby the resistance to unwinding of the springs is gradually decreased as the springs unwind so that a comparatively great resistance is exercised to the unwinding of the springs at the time when they are under the greatest tension and thus have the most power and a comparatively low resistance to the unwinding of the springs is exercised at the time when they have unwound and thus lost some of their driving effect, the drive thus being substantially uniform under all conditions of the spring from fully wound to unwound.

A fourth important object of the invention is to provide a novel means for controlling a braking mechanism, the means being so arranged that as the main springs unwind the braking effect on the wheel train is gradually lessened.

A fifth important object of the invention is to provide an improved escapement arrangement for such a clock.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front elevation of the clock with the dial removed.

Figure 2 is a side elevation thereof taken from the right side of Figure 1.

Figure 3 is a plan view of the clockworks.

Figure 4 is a section on the line 4—4 of Figure 2.

Figure 5 is a section on the line 5—5 of Figure 2.

Figure 6 is a section on the line 6—6 of Figure 1.

Figure 7 is a section on the line 7—7 of Figure 1.

Figure 8 is a section on the line 8—8 of Figure 1.

Figure 9 is a top view of the regulator or escapement train.

In the embodiment of the invention herein illustrated the dial is omitted for the purposes of more clearly showing the working parts but it is to be understood that any desired dial may be used with these clockworks. The frame of the clock includes a back plate 10 and a front plate 11 which are held in suitable spaced relation by the posts 12.

Journaled in the front and back plates is an arbor 13 which I preferably term the main arbor and on this arbor is fixed a main arbor gear 14 wherewith meshes the lateral driving gears 15 mounted on lateral winding arbors 16. Also a lower driving gear 17 meshes with the main arbor gear 14, being carried on a lower winding arbor 18. Surrounding the arbors 16 and 18 are the main springs 19, these springs being of the usual flat spirally wound form and each having one end fixed in the ordinary manner to its arbor and the other end carried by one of the posts 12. Fixed on each of the driving gears is a winding ratchet 20 and each of these ratchets is engaged by a respective winding pawl 21 pressed into rapid engaging position by a winding pawl spring 22, the pawl and spring being mounted on the respective driving gear. Thus the springs may be wound without rotating the driving gears but unwinding of the springs causes rotation

of the driving gears and consequently rotates the main arbor 13. On the main arbor 13 is fixed a second gear 23 which meshes with a lantern pinion 24 fixed on a second arbor 25 journaled in the front and back plates. On this second arbor is also mounted a driving gear 26 which meshes with a lantern pinion or gear 27 mounted on the third

arbor 28. This third arbor 28 extends through the front plate 11 and on its forward end is carried a disk serving the purpose of a friction clutch member. On that 5 portion of the arbor which extends in front of the plate 11 is revolubly mounted a driving gear 30 which is pressed against the clutch member 29 by a flat leaf spring 31 having an opening for receiving the arbor 10 28 and bowed so that its central portion rests against the front plate 11 while its ends bear against the rim of the gear 30. This gear 30 meshes with a minute pinion 32 mounted on a sleeve 33 revoluble on the staff 34 which 15 projects forwardly from the plate 11, being fixed thereto. Also the minute pinion 32 meshes with a gear 35 mounted on a staff or stub shaft 36 to revolve thereon. Fixed to the gear 35 is a driving pinion 37 which 20 meshes with the hour gear 38 mounted on a sleeve 39 revolving on the sleeve 33. The clock is provided with the usual minute hand 40 and hour hand 41 pressed on the respective sleeves. Now, it will be, of course, 25 realized that the gears 32, 35, 37 and 38 are so proportioned that the hour hand revolves once for each twelve revolutions of the minute hand as is the usual manner. It will also be noted that by reason of the spring 30 pressed clutch arrangement the hour and minute trains may be rotated without the rotation of the arbor 28 and consequently without interfering with the driving train including the gear 33 at one end and the 35 gears 15 and 17 at the other end. Furthermore, the proportions of the various driving and driven gears in this train are such that the complete unwindings of the springs to such extent as to make rewinding essential 40 does not occur until the hour hand has made a large number of complete revolutions, say eight hundred, thus enabling the clock to run for four hundred days without requiring rewinding.

45 Fixed on the arbor 25 is a brake disk 42 and through the front plate 11 extends a brake plunger 43 which has on its rear end a brake shoe 44 of leather or other suitable material, this brake shoe bearing against the 50 front face of the brake disk. The plunger is slidably mounted in the front plate so that it can be forced more or less firmly into contact with the brake disk. Mounted on the front plate is a lever fulcrum post 45 and a lever 46 is pivoted intermediate its ends to this post. To the upper end of the lever 46 is fixed a leaf spring 47 which carries the plunger 43 so that as the lever is rocked in one direction the brake will be applied while, 55 upon the rocking of the lever in the other direction the brake will be relaxed. The lower end of the lever rests on the tapered cam flange 48 of a cam disk 49 mounted to rotate on a cam shaft 50. On this cam shaft 60 65 is also mounted a Geneva wheel 51 and on the

arbor 18 is mounted a single toothed gear 52 forming the Geneva gear and meshing with the Geneva wheel 51. The gear 52 is secured by suitable means on the shaft or arbor 18 and thus as the arbor is winding up the clock 70 the cam receives a step by step rotation until the lever is in engagement with the high part of the cam. At this time the spring 47 is under its greatest tension and the brake is most heavily applied. One section 51a of the Geneva wheel 51 is enlarged for engagement with the gear 52 to prevent overwinding. As the main spring unwinds, the Geneva wheel is rotated in the opposite direction by a step 75 by step movement and the cam rotates to gradually lower the end of the lever in engagement therewith and thus gradually relaxes the pressure of the brake on the brake disk so that the decrease in effective force of the springs as they unwind is compensated by the decrease of braking effect on the multiplying train between the spring arbors and the third arbor. Thus the third arbor has substantially the same torque under all conditions of spring winding. 80 85 90

On the third arbor 28 is also fixed a rear driving gear 53 which meshes with a lantern pinion 54 on the fourth arbor 55. This fourth arbor is journaled in the plates 10 and 11 and also carries a driving gear 56. On top of the plates 10 and 11 is an escapement train base plate 57 which supports an escapement train 58 driving the escapement wheel 59 which is controlled by an escapement lever 60 oscillating under the influence of the usual spring controlled balance wheel 61, the oscillations of this wheel being controlled in the usual manner by the regulator lever 62. The escapement train 58 includes a first wheel 63 which meshes with the driving gear 56 so that the escapement train is driven from this gear. It will be observed that the staffs of the escapement train are vertical while the staffs of the main clock trains are horizontal, the gears 56 and 63 thus meshing at right angles. By this means the escapement train is very compactly associated with the main trains. 100 105 110

In use all three of the main springs are wound up fully at the start of operations and, as previously described, this will apply the brake fully. Consequently, as the three main springs run down the brake will be relaxed and the driving train will have a substantially uniform effect on the hour and minute train and the escapement train under all conditions of spring windings. 115 120

There has thus been provided a simple and efficient device of the kind described and for the purpose specified. 125

It is obvious that minor changes may be made in the form and construction of the invention without departing from the material spirit thereof. It is not, therefore, desired to confine the invention to the exact 130

form herein shown and described, but it is desired to include all such as properly come within the scope claimed.

Having thus described the invention, what is claimed as new, is:

1. In a clockwork mechanism, a spring driven arbor, a brake disk geared to said arbor, a brake bearing on said disk, a brake spring urging the brake against the disk, a lever supporting said spring and tilttable in one direction to increase the tension of the spring and in the other direction to decrease said tension, and a cam actuated by the movement of the arbor and engaging the lever to tilt the lever in said respective directions according to the winding and unwinding movements of the arbor.

2. In a clockwork mechanism, a spring driven arbor, a brake disk geared to said arbor, a brake bearing on said disk, a brake spring urging the brake against the disk, a lever supporting said spring and tilttable in one direction to increase the tension of the spring and in the other direction to decrease said tension, a cam engaging said lever to tension the brake spring and revolute to vary said tension, a Geneva wheel fixed to said cam, and a Geneva gear fixed on said spring arbor and meshing with the Geneva wheel 20 to rotate the latter in a step by step movement as the arbor rotates.

3. In a clockwork mechanism, a driving train, and an hour and minute train geared to the driving train and parallel to said driving train, said driving train including a frictionally clutched terminal gear meshing with the first gear of the hour and minute train and a spring driven arbor, a brake disk geared to said arbor, a brake bearing on said disk, a brake spring urging the brake against the disk, a lever supporting said spring and tilttable in one direction to increase the tension of the spring and in the other direction to decrease said tension, and a cam actuated by the movement of the arbor and engaging the lever to tilt the lever in said respective directions according to the winding and unwinding movements of the arbor.

4. In a clockwork mechanism, a driving train, an hour and minute train geared to the driving train and parallel to said driving train, and a braking mechanism normally braking the action of the driving train and geared to said driving train to gradually relax as the clockworks run down including a spring arbor, a brake disk geared to said arbor, a brake bearing on said disk, a brake spring urging the brake against the disk, a lever supporting said spring and tilttable in one direction to increase the tension of the spring and in the other direction to decrease said tension, and a cam actuated by the movement of the arbor and engaging the lever to tilt the lever in said respective directions ac-

cording to the winding and unwinding movements of the arbor.

5. In a clockwork mechanism, a driving train, an hour and minute train geared to the driving train and parallel to said driving train, said driving train including a frictionally clutched terminal gear meshing with the first gear of the hour and minute train, and a braking mechanism normally braking the action of the driving train and geared to said driving train to gradually relax as the clockworks run down and including a spring driven arbor, a brake disk geared to said arbor, a brake bearing on said disk, a brake spring urging the brake against the disk, a lever supporting said spring and tilttable in one direction to increase the tension of the spring and in the other direction to decrease said tension, a cam engaging said lever to tension the brake spring and revolute to vary said tension, a Geneva wheel fixed to said cam, and a Geneva gear fixed on said spring arbor and meshing with the Geneva wheel to rotate the latter in a step by step movement as the arbor rotates.

In testimony whereof I affix my signature.
